PAGE 3

Fig. 5.

Fig. 6.

FIGURE 1 is a front perspective view of a phonograph cabinet embodying my new design;

FIGURE 2 is a right side elevational view;

FIGURE 3 is a front elevational view;

FIGURE 4 is a top plan view;

FIGURE 5 is a rear perspective view; and

FIGURE 6 is a front perspective view of the phonograph cabinet shown in FIGURE 1 wherein the front grill above the speaker units is plain and unornamented except for a single row of rectangular projections near the bottom of the grill.

The side, top and rear views of both embodiments of the design for a phonograph cabinet are identical.

The dominant features of my design reside in the portion shown in full lines.

I claim:

The ornamental design for a phonograph cabinet, as shown and described.
